UNITED STATES PATENT OFFICE.

PHILLIP HIEN, OF CHICAGO, ILLINOIS, ASSIGNOR TO DAVID S. WEGG, OF SAME PLACE.

DESIGN FOR A LOCK FOR LIFTING-PINS FOR CAR-COUPINGS.

SPECIFICATION forming part of Design No. 33,757, dated December 18, 1900.

Application filed November 24, 1900. Serial No. 37,687. Term of patent 14 years.

To all whom it may concern:

Be it known that I, PHILLIP HIEN, a citizen of the United States, and a resident of Chicago, in the county of Cook and State of Illinois, have invented and produced a new and original Design for a Lock for Lifting-Pins for Car-Couplers, of which the following is a specification, reference being had to the accompanying drawings, and to the letters of reference marked thereon, which form a part thereof.

In said drawings, Figure 1 is a side elevation of a device embodying my invention. Fig. 2 is a top plan view of the same. Fig. 3 is a section taken on line 3 3 of Fig. 2. Fig. 4 is a section taken on line 4 4 of Fig. 2. Fig. 5 is a section taken on line 5 5 of Fig. 2.

As shown in said drawings, A indicates a clevis of iron or other suitable material, one of the arms of which is provided on one side with a laterally-extending projection B, the end of which is turned downwardly and obliquely, forming an arm B'. The lower end of the said arm is provided at its extremity with a hook b, directed inwardly and approximately parallel with the projection B. Said projection B is approximately semicircular in cross-section, as indicated in Fig. 5, and the downwardly-extending arm B' and hook b are

approximately flat on their inner sides and convex on their outer sides, as indicated in Fig. 3. Each arm of the clevis is provided at its extremity with a projection C, extending approximately opposite from the hooked arm B' beyond the pivot-apertures and adapted to engage a surface on the part to which said clevis is pivoted and designed to prevent said clevis being elevated to a position perpendicular to said surface.

The material or essential features of my design are a clevis provided on one side with a laterally and rearwardly directed hooked arm and provided at its ends with projections extending approximately opposite said hooked arm.

Having described my invention, what I claim as new, and desire to secure by Letters Patent, is—

The design for a lock for lifting-pins for car-couplers, substantially as shown and described.

In testimony whereof I have hereunto subscribed my name in the presence of two subscribing witnesses.

PHILLIP HIEN.
